W. H. BUCKLEY,
SPARK PLUG,
APPLICATION FILED SEPT. 16, 1915.

1,177,924.

Patented Apr. 4, 1916.

UNITED STATES PATENT OFFICE.

WILLIAM H. BUCKLEY, OF BRIDGEPORT, CONNECTICUT.

SPARK-PLUG.

1.177.924.

Specification of Letters Patent.

Patented Apr. 4, 1916.

Application filed September 16, 1915. Serial No. 50,940.

To all whom it may concern:

Be it known that I, WILLIAM H. BUCKLEY, a citizen of the United States, residing at the city of Bridgeport, county of Fairfield, State 5 of Connecticut, have invented certain new and useful Improvements in Spark-Plugs; and I do declare the following to be a full, clear, and exact description of the invention, such as will enable others skilled in the art to which it appertains to make and use the same.

My present invention pertains to an improved spark plug for explosive engines, the construction and advantages of which will 15 be hereinafter set forth, reference being had to the annexed drawings, wherein:

Figure 1 is a longitudinal sectional view of the plug, the positive or central electrode being shown in full; and Fig. 2 a bottom 20 plan view thereof.

Spark plugs of the same general type as that which forms the basis of this invention are old and many have been patented and also used with a greater or less degree of success. So far as I am aware, however, such 25 plugs are open to several objections, the main ones being that of short-circuiting, burning of the electrodes, smutting, and the deposition of carbon on the electrodes, with 30 the consequent weakening of the spark, and diffusion of the spark, causing weakening, whereby the spark oftentimes fails to ignite the charge.

The object of the present invention is to 35 produce a structure wherein these objections and difficulties will be overcome or obviated, and that by a construction which is at once simple and incapable of misadjustment in assembling.

Referring to the drawings, 1 denotes the usual shell, the lower end 2 whereof is cylindrical and externally threaded whereby it may be screwed in place in the engine cylinder. Said shell forms the grounded electrode. The upper portion of the bore of the 45 shell is preferably enlarged, a shoulder 3 being thereby produced upon which the shoudered portion 4 of the insulating plug or bushing 5 finds its seat. A nut 6, engaging a second shoulder 7, upon the bushing, is screwed upon the upper end of the shell, suitable packing, as 8, being interposed to 50 effect a gas-tight joint, and the bushing is thus held in place.

The insulating bushing, formed of any suitable di-electric material, is provided with a

longitudinal bore which is concentric with the inner cylindrical bore of the lower end 2 of the shell, and as will be noted the lower portion 9 of the bore is larger in diameter 60 than the upper portion, an inclined shoulder 10, being formed at the point of mergence of the different sections of the bore.

A stem or wire 11, threaded at its upper end for the reception of suitable nuts and washers, indicated generally by 12, for connection of the current conductor, extends through the upper bore of the insulating bushing. The stem carries a head or enlargement 13 at its lower end, which fits 70 against shoulder 10. Suitable packing may be interposed at this point, to effect a gas-tight joint. Head 13 is internally threaded and a second stem or wire, 14, is screwed into the same, the stem standing away from 75 the wall of the bushing and extending downwardly below the lower end of the same a considerable distance, terminating in a laterally-projecting toe 15. Said toe, which is formed integrally with the stem, is 80 flattened, and the outer end thereof is curved, the curve being somewhat sharper than that of the inner cylindrical wall of the lower end 2 of the shell 1; in other words, the curved faces are eccentrically arranged. It will also be noted that the end 85 of the toe or terminal is lightly curved upon its upper and lower faces, and by thus curving the same in all directions no points or angles are present at which the current 90 would have a tendency to localize and jump to the bushing or grounded terminal.

With this construction there is presented a spot or space on the toe which is at the exact or proper sparking distance from the 95 inner wall of the bushing, and by making the surface of the toe curved there can be no burning away, because no undue concentration or localization of the current will take place, the current merely flowing around 100 the curved surface to the spot or space where the discharge is effected. Again, the current may be said to be gathered to the place of discharge, and consequently there is no 105 breaking up of the current into separate sparks or discharges, as is bound to take place where there are any points or angles present on either terminal.

By having the stem or wire 14 extend a considerable distance below the insulating 110 bushing 5, the terminal is subjected to the scouring action of the gas as it flows into

and out of the engine cylinder and consequently it is kept clean at all times, thereby insuring a full discharge when required. Furthermore, there are no metallic fastenings or points where the current would have a tendency to jump across to the bushing, thus destroying the efficiency of the plug.

It is manifest that instead of forming the positive electrode in two sections, 11 and 14, it may be produced from a single piece, but for obvious reasons the two-piece construction is preferred. It will also be appreciated that there can be no misplacement of the toe with reference to the wall of the lower portion 2, as the stem 14 and said wall have a common axis or center, hence care or fine adjustment in assemblage is unnecessary.

Having thus described my invention, what I claim is:

- 20 1. In a spark plug for explosive engines, the combination of a shell having a curved inner face adjacent its lower end forming one electrode; an insulating bushing mounted in the shell; and an electrode mounted in the bushing, extending below the same and terminating in a single laterally-extending toe, that face or end of the toe which extends toward the wall of the shell being curved,

the curvature being sharper than that of the 30 aforesaid inner face of the shell, said last-named electrode being free of any projections other than said toe, and the body of the electrode gradually merging into the toe.

2. In a spark plug for explosive engines, 35 the combination of a shell having a cylindrical inner surface, at its lower end, and forming one electrode; an insulating bushing mounted in the shell; and an electrode mounted in the bushing and extending below the same, the end of said electrode projecting laterally, within the shell, in the shape of a toe, terminating adjacent the cylindrical surface aforesaid, and being free of other projections, the end or extremity of 40 said toe nearest the shell being curved laterally upon a radius smaller than that of the cylindrical surface, and likewise being slightly curved upon its upper and lower faces adjacent said laterally curved end, 45 whereby an extended curved surface is formed free of all points or projections.

In testimony whereof I affix my signature in presence of two witnesses.

WILLIAM H. BUCKLEY.
